[57] CLAIM

The ornamental design for a cabinet, as shown and described.

DESCRIPTION

FIG. 1 is a perspective view of a cabinet showing my new design; the opposite side not shown being a mirror image thereof;

FIG. 2 is a front elevational view thereof;

FIG. 3 is an enlarged fragmentary perspective view of the front upper left end corner;

FIG. 4 is an enlarged fragmentary front elevational view thereof; and

FIG. 5 is an enlarged fragmentary sectional view taken along line 5—5 of FIG. 3.

The characteristic feature of my design resides in the edge appearance.
